UNITED STATES PATENT OFFICE.

CLAIBORNE W. GOOCH, OF LYNCHBURG, VIRGINIA, ASSIGNOR TO BURROUGHS ADDING MACHINE COMPANY, OF DETROIT, MICHIGAN, A CORPORATION OF MICHIGAN.

ADDING-MACHINE.

No. 825,205.

Specification of Letters Patent.

Patented July 3, 1906.

Application filed December 2, 1905. Serial No. 290,009.

To all whom it may concern:

Be it known that I, CLAIBORNE W. Gooch, a citizen of the United States, residing at Lynchburg, in the county of Campbell and State of Virginia, have invented certain new and useful Improvements in Adding-Machines, of which the following is a specification.

My invention relates to adding-machines of that class adapted to print and list individual items and to accumulate and print the totals thereof and also to print such total at the will of the operator, such class of machines being exemplified by the well-known Burroughs adding-machine constructed and operating in substantial accordance with Burroughs' patents, Nos. 504,963 and 505,078, issued on September 12, 1893.

The object of my invention is to provide a novel and efficient mechanism for splitting the machine into a plurality of separate sections, whereby the sections may be employed for printing and accumulating items of different character.

Another object of my invention is to make provision for changing in convenient manner the line or point of split and for locating it at any line or point between any two denominations of the regular machine and also to make provision for splitting the machine at a plurality of lines, whereby the machine may be split in three or more sections, as may be desired.

My invention has for its further object the elimination of one or more sections so far as the printing of the total accumulated thereon is concerned, whereby the total of those items only which are required to be accumulated and their total to be printed is recorded.

My invention embodies other novel and advantageous features of construction and operation, which will be apparent from the description hereinafter given.

In the drawings, Figure 1 is a left-hand side elevation of a Burroughs machine, but illustrating only those parts of such machine which are more or less concerned with my improvements; Fig. 2, a sectional elevation of the printing mechanism of the machine; Fig. 3, a plan view of the printing mechanism with the sections 611 and their type and also the pawls 718 removed and with the hammers in section; Figs. 4 and 5, sections on

lines 4 and 5, respectively, of Fig. 3, the same being detail views of the lower ends of two hammers, illustrating differences in construction between them; Fig. 6, a perspective of the coupler and two of the special latches 717 with which such coupler co-operates at the line of split; Fig. 7, a detail view of certain parts of the machine and of my improvements, illustrating the relative position of such parts at the time when the totalizing mechanism is operated and the printing action as to one of the sections is eliminated, and Figs. 8, 9, and 10 perspectives of certain parts of the attachment constituting my improvement.

Although I have illustrated and will hereinafter describe my invention as embodied in a Burroughs machine, yet it will be understood that my invention is not to be limited in its application to this particular make or style of machine, inasmuch as my invention may find useful application in adding-machines of other makes and other constructions. Moreover, inasmuch as my invention has more particular relation to the printing and totalizing mechanisms, the other mechanisms of the complete adding-machine have been omitted; but for an understanding and detail description thereof reference may be had to the aforesaid Burroughs patents.

As is well known, a Burroughs adding-machine is provided with a series of keys 291, mounted in a keyboard and arranged in rows or banks representing different denominations, increasing from right to left, and of a number according to the desired capacity of the machine, the keys in each row being numbered from "1" to "9" to represent the different digits for each denomination. These keys are arranged to control the extent of movement or oscillation of a series of main levers or sectors 611, mounted or hung upon a main transverse shaft 600, each row of keys being provided with a corresponding sector 611. Each of these sectors is provided at its rearward end with a series of five separate and movable type-plates 618, each plate bearing two separate type and all of the type of each sector representing the nine digits and the cipher. The other or forward end of each sector 611 is provided with a rack 610, whose degree of descent is determined by the value of the particular key depressed or set in its

corresponding row of keys. Each rack 610 meshes with its corresponding pinion 916, forming a part of the accumulating mechanism and provided with the usual adding wheel or dial 912. The descent of the rack 610 through the distance permitted by the particular key depressed raises the rearward or type-bearing end of the sector 611, so as to present the particular type corresponding in value to the key depressed to the printing-line of the platen or paper-support 1599, with the result that when the hammer 715, forming a part of the printing mechanism, is operated such particular type will be impressed upon the paper on the platen.

The series of accumulating-pinions 916 are mounted in a rocking frame composed of side plates 910 and arranged to rock or swing upon an axis or shaft 900. This rocking frame is operated by moving parts of the machine in such manner that upon the initial movement of the main operating-shaft of the machine the pinions are all rocked out of mesh with their racks 610, so as to permit the racks corresponding to the rows of keys in which the keys have been set or depressed to descend distances corresponding to the value of such depressed keys. Upon the further operation of the machine and immediately before the ascent of the racks the accumulating-pinions are swung back into mesh with their racks, with the result that such pinions will be turned by those racks which have been operated, as stated, so that the item set up on the keyboard will be transferred to the accumulating-pinions. In the present instance these means for so controlling the operation or rocking movement of the pinions comprise a main rocking lever 813, mounted on the main rocking-shaft 800 and carrying at its upper end a wipe-plate 821, which is adapted to coöperate with the three-arm lever 913, with the result that such lever is oscillated first in one direction and then in the other in each complete operation of the machine. The lower or depending arm of the lever 913 is pivotally connected to a pitman 914, whose forward end is arranged to coöperate with the rocking frame 910 of the pinions in the usual and well-known manner to accomplish the results just stated. To control the operation of the pitman 914 and consequently the operation of the rocking frame 910 for the purpose of permitting a total or a subtotal to be taken at the will of the operator, there is a total-key 293, which is connected with a bell-crank 227^L and also operatively connected with the pitman 914 through the medium of the vertical link 911. As is well known, the depression of the total-key 293 during a complete operation of the machine causes a total to be printed and also the depression of such total-key during the forward movement of the operating-handle of the machine, and the release of

that key during the return movement of such operating-handle or main shaft of the machine causes a subtotal to be printed. The depression of the total-key interferes with the usual operation of the pitman 914 by preventing the forward rocking of the pinion-frame, with the result that the pinions are left in mesh with their racks during the descent of the latter, and such racks descend distances as permitted by the pinions which are returned to zero; so that the amount thereupon presented by the type to the platen corresponds to the accumulation on the pinions 916. If the total-key is held depressed during a complete operation of the machine, the pinion-frame is caused to be swung forwardly out of mesh with the racks and kept in such non-engaging position in the ascent or restoration of such racks, so that the pinions which have been reset to zero position in such totaling operation are left in that position. In other words, a grand total has been taken, and the machine has been cleared. If now after the total has been printed, as just stated, the total-key is released and permitted to ascend to normal position, the pinion-frame will not be swung out of mesh with the racks, but left in mesh, so that the values which have been transferred from the pinions to the racks will now be transferred back again. In other words, the particular total which has been taken is a subtotal, for the accumulation has been retained in the machine. As herein shown, in Figs. 1 and 7 the bell-crank 227^L is connected, as usual, with the horizontal link 226, which is in turn connected with the depending arm 227^{1/4}^L, certain parts of my attachment, as hereinafter described, being arranged to coöperate with such link 226.

Referring next to the printing mechanism of the Burroughs machine, the same comprises a series of vertical hammers 715, one for each sector 611 and all mounted on a cross rod or shaft 701, supported at its ends in the frame of the printing mechanism, composed of the right-hand-side plate 710^R and the left-hand-side plate 710^L, both of which are mounted upon the shaft 600. These hammers are actuated by drivers 716, mounted on a cross-shaft 702 in the printing-frame and provided with studs 753, located near their upper ends and arranged to be received within the curved slot 715^a of its hammer. Each driver and its hammer is normally held retracted, but upon the release of the driver the hammer is driven rearwardly by the action of the stud 753 in the slot of the hammer. Each driver 716 is under the control of its latch 717, whose lower edge is provided with a shoulder or hook to engage the upper end of its driver, it being understood that there are as many of these latches as there are hammers and

drivers. These latches 717 are mounted upon a cross-shaft 700 in the printing-frame and are in turn controlled by a series of pawls 718, corresponding in number to the 5 number of hammers, drivers, and latches mounted on a cross-shaft 704, supported at its ends in a frame arranged to oscillate in the operation of the machine and provided with rearward hook-shaped ends adapted to 10 rest upon the upper edge of their latches and to engage shoulders thereon in case their corresponding levers 611 have been operated, but prevented from such actuation of their latches 717 by reason of the contact of the 15 tails of such pawls against the inclined shoulders 611^a of the sectors 611 when in their normal or non-operative position, with the result that at such times the pawls 718 will be swung upwardly as to their rearward 20 ends, so as to clear the shoulders on the upper edges of their latches. In order to provide for the transfer of the hammer action from left to right for the printing of ciphers, the latches 717 are provided with tails *d*, 25 which are extended laterally, so as to overlie the forward ends of the next succeeding latches on the right, as clearly indicated in Fig. 3. The construction of printing mechanism as just described is that which is common in the ordinary Burroughs machine; but in the present instance, which contemplates the splitting of the machine and particularly of the printing mechanism, I provide two special forms of latches 717, which 30 are illustrated in perspective in Fig. 6. Before describing the construction and mode of operation and purposes of these special latches I will state that the same may be disposed or assembled at any particular 35 point or line in the series of regular latches 717 and also that any desired number of sets of these special latches may be provided and assembled at any desired number of points among the series of regular latches, according 40 to the number of sections into which it is desired to split the machine. Referring to these special latches, one of them (marked 45 717^a) is the same as a regular latch 717, with the exception of the omission of the tail *d* and the provision of a recess 717^b on its upper edge, such recess having its rearward side straight or vertical and its front side sloping, as clearly indicated in Fig. 6. The 50 other special latch 717^c is similar to a regular latch 717, with the single exception of the provision of a recess 717^d on its upper edge, whose respective sloping and straight sides are the reverse of those of the other special latch, inasmuch as in the special latch 717^c it is the front side of the recess which is formed abrupt or straight. This second 55 special latch is, however, provided with the usual tail *d*, like the regular form of latch. Inasmuch as the transferring-tail *d* of the 60 special latch 717^a is omitted the machine is split at a line or point between the special latches, and so far as the machine has been described the hammer action cannot be transferred from the left to the right of such line of split. However, provision is made 65 for bridging this line of split when it is desired to operate the machine in its entirety as a regular machine operating with the full capacity of keyboard, and in the present instance such bridging is accomplished 70 through the medium of what I will term a "coupler," marked A and clearly illustrated 75 in Fig. 6, where such coupler is shown grouped with the two special latches, but not in co-operative relationship therewith. The 80 construction and arrangement are such that when this coupler is in operative relationship with the latches the line of split is bridged and the latches transfer the hammer action for cipher-printing in the same manner as if 85 the special latch 717^a were provided with the transferring-tail *d*. The coupler consists of a curved arm, whose forward end is provided with an open-ended slot *a*, whereby such coupler may be slipped over the transverse 90 rod or shaft 706, secured at its ends in the side plates 710ⁿ and 710^l. The rearward end of the coupler is provided with two laterally-extending pins *a*² and *a*³, which may, however, be a single pin extending 95 through the coupler and projecting from either side thereof, although for convenience in description the same will be hereinafter referred to as two separate pins. The pin *a*² is arranged to be received within the recess 100 717^b of the special latch 717^a, when such coupler is in position to bridge the line of split and to couple the two special latches. The other pin *a*³ is arranged to be received within the recess 717^d when such coupler is 105 in its operative position. It will be obvious that when the coupler is in its operative position, with its two pins within the recesses of the special latches, as indicated in Fig. 2, the oscillation of the special latch 717^a, caused 110 either by reason of actuation from its own pawl 717 or from actuation by the tail *d* of the next adjacent but regular latch on the left, will move the coupler forwardly in unison with the special latch 717^a, it being understood 115 that the abrupt side or wall of the recess 717^b will at this time press against the pin *a*². This movement of the special latch 717^a and of the coupler is transmitted to the other special latch 717^c by reason of the pressure of the pin *a*³ against the abrupt side or wall of the recess 717^d. Thus the special latch 717^c is oscillated in substantial unison 120 with its companion special latch, to thereby release its own hammer-driver and also 125 cause the tripping of all of the latches to the right for cipher-printing. When, however, the coupler A is moved or oscillated up-

wardly to thereby remove its pins a^2 from the recesses of the special latches by mechanism hereinafter described, the machine operates as a split machine, with the line of split between the two special latches.

While in the present instance the line of split is between the sixth and seventh denominations, inasmuch as the special latches correspond to such denominations it is evident, as hereinbefore stated, that these special latches may be disposed or assembled at other positions relative to the series of regular latches in order to bring the line of split between any other two denominations of the machine. Also, as hereinbefore suggested, a plurality of sets of special latches and a corresponding plurality of couplers may be employed in the same machine in order to split the machine at a plurality of points or lines, it being understood that for this purpose additional sets of these special latches and couplers are employed. In order to enable the line of split to be changed conveniently and at will and also to enable a plurality of sets of special latches to be employed in the machine, I so construct the cross-shaft 706, on which the coupler is pivotally mounted, that such coupler may be adjusted to a plurality of positions corresponding to the spaces between the latches and also in such manner that such shaft may receive additional couplers along its length and properly position and retain them. As indicated in Figs. 2 and 3, this shaft 706 is provided with a series of deep circumferential grooves 706^a, which correspond in position to the spaces between the latches and which are adapted to receive the forward end of the coupler or of a plurality of couplers. As shown clearly in Figs. 2, 3, and 4, the construction of the coupler is such that it may be readily removed from its supporting-shaft 706 and placed in any other groove 706^a of such shaft, and at the same time the set of special latches is correspondingly adjusted along the shaft 700 by substitution for two regular latches.

The mechanism, which is under the control of the operator, for operating the coupler A, and thereby determining whether the machine is split or normal, comprises a bail B, whose parallel arms are connected to a cross-rod b , journaled in the side plates of the frame of the printing mechanism, although, as will be evident, an operating connection extending only to the movable arm or coupler A would be required in case the coupler had a relatively fixed position transversely of the printing mechanism. When the bail is moved downwardly in the manner hereinafter explained, the forward end of the coupler is likewise downwardly moved and the rearward end of the coupler correspondingly elevated to remove the same from coöperating relationship with the special latches. This bail extends entirely across the width of the

printing mechanism in order that it may be enabled to contact and operate a coupler to whatever position the latter may be adjusted or to contact and operate all of a series of such couplers disposed along the length of the supporting-rod or rock-shaft 706, as will be obvious from an inspection of Fig. 3. This bail is in the present instance key-controlled by reason of the provision of a special key C and operating connections between the bail and such key. In the present instance the shaft b is extended through the side plate 710^L of the frame of the printing mechanism and provided with a depending crank-arm b' , having at its lower end a stud b^2 . This stud is operatively connected with a reciprocating link or operating-arm D, having its forward end upwardly curved or extended and there operatively connected with a crank-arm e on a second rock-shaft E, suitably journaled at its ends within the machine. This rock-shaft is provided at a point toward its left-hand end—that is, toward the left-hand side of the machine—with a second crank-arm e' , having a long stud E^2 extending laterally toward the left, Fig. 10. This stud e^2 is arranged in the path of movement of the stem c of the special key C, with the result that when such special key is depressed the rock-shaft E is rocked in an anti-clockwise direction when viewed as in Fig. 1, and the machine is changed from a complete to a split machine by operation of the connections, as hereinbefore more particularly explained.

As clearly indicated in Fig. 1, the stem of the special key is irregular shaped, having two bends providing two substantially vertical portions and a connecting horizontal portion, with the extreme lower end longitudinally slotted in order to fit over and be guided by the cross-shaft 600 of the machine, Figs. 1, 7, and 9. The rearward edge of the extreme lower end of this key-stem is extended, so as to provide a contact-surface c' to bear against the long stud e^2 . When the special key C is depressed, the entire key-stem is bodily depressed, and when the key is fully depressed the shaft 600 is positioned at the upper end of the slot in such key-stem. The special key is arranged to be held in two different depressed positions—to wit, a position of full depression and an intermediate position—to which end the upper portion of the key-stem is provided with two shoulders c^2 c^3 , arranged to lock under the lower plate 212 of the keyboard. However, so far as the mechanism for splitting the machine is concerned only one of these positions of the key-stem is necessary, inasmuch as the depression of the key beyond said intermediate position has no effect upon the bail B, the full movement thereof being accomplished in the first portion of the depression of the special key.

As hereinbefore stated, the stud b^2 of the bail is operatively connected with the operat-

ing arm or link D; but in the present instance this connection consists of a coiled spring b^3 , fastened at one end to the crank-arm b' and at the other end to the link D intermediate 5 the length of the latter, as clearly indicated in Figs. 1, 3, and 7. Moreover, the link D is provided with an open-ended slot to receive the stud b^2 , the inner end of the slot being held against such stud by the tension of the 10 spring b^3 , which holds both the link D and the rock-shaft E in the normal position, which is indicated in Fig. 1. When, however, the shaft E is rocked positively by the depression of the special key C, as hereinbefore 15 described, the link D is moved or reciprocated rearwardly, thereby tending to withdraw the end of the slot thereof from the stud b^2 ; but by reason of the provision of the spring b^3 such stud follows up the link D, and 20 thereby permits the bail B to rock downwardly, with the result that the coupler A is moved up to an inoperative position with its pins a^2 and a^3 out of coöperative relationship with the special latches, under which 25 conditions the machine is a split one. As hereinbefore suggested, it is immaterial so far as the splitting mechanism is concerned whether the key is depressed to the first or second notch or shoulder, inasmuch as the depression 30 to the first shoulder is sufficient and without further effect upon the bail B, because the contact-surface c' simply continues to slide on the long stud e^2 without further effect on the latter. Upon the release of the 35 special key the latter is restored to normal or elevated position by the tension of its spring c^4 , and the rock-shaft E and the link D and also the bail B are restored by means of the action of the spring b^3 .

40 In addition to the above-described mechanism for splitting the machine I provide mechanism coöperating therewith for eliminating the printing action of any one or more of the sections into which the machine is 45 split. In the present instance I have shown such additional mechanism as arranged to coöperate with the left-hand section of a split machine, although, as will be understood and will be hereinafter made apparent, such 50 additional mechanism may be arranged to coöperate with the right-hand section or with any one or more sections of a split machine having a plurality of lines of split. Moreover, the construction and arrangement 55 is such that the additional mechanism is caused to operate to eliminate the printing action of its section in an automatic manner and by the act of taking a total with the machine, such mechanism being in the present 60 instance under the control of the totalizing mechanism.

Referring to the present construction, the mechanism for so eliminating the printing action of a section of a split machine comprises a bail F with its parallel arms connect- ed with a rock-shaft f, journaled at its ends in the side plates of the frame of the printing mechanism. The left-hand end of this rock-shaft f extends through the side plate 710^L and is there provided with a bent crank-arm f' , 70 having at its extreme end a pin or stud f^2 , which is received by an open-ended slot in the rearward end of the link or operating-arm D. This bail F is held in its raised or inoperative position away from the hammers 715, as clearly indicated in Fig. 2, with a yielding pressure, in the present instance by means of a spring f^3 , fastened at one end to the crank-arm f' and at the other end to a pin f^4 , extending from the side plate 710^L, as 80 seen in Fig. 3. When the bail F is in the normal or elevated position (indicated in Figs. 1 and 2,) all of the series of hammers are free to operate in the usual and well-known manner hereinbefore described; but when such 85 bail is rocked downwardly to the position indicated in Fig. 7 by operating connections hereinafter described the bail is swung into the vertical plane of movement of all of the hammers and serves to arrest all of the hammers of the left-hand section of the machine; but none of the hammers of the right-hand section of the machine are interfered with by the bail, owing to the fact that the hammers of this latter section are cut away at 715^b, as 90 clearly indicated in Fig. 4, whereas the hammers of the left-hand section of the machine remain of the usual construction, as indicated in Fig. 5. It results from this construction and arrangement that while the 100 hammers of the right-hand section of the machine are permitted to operate in the usual manner to strike their type-plates and cause the impression the hammers of the left-hand section are prevented from operating, inasmuch as after a partial rearward movement 105 the same are arrested and prevented from delivering their blows upon their type-plates, so that under these conditions the printing mechanism of the left-hand section of the 110 machine is inoperative and no impression will be made notwithstanding the existence of an accumulation on the accumulating-pinions corresponding to this particular section of the machine and notwithstanding also the 115 elevation of the corresponding type-plates to printing position.

It will be understood that the printing-controlling bail F is not directly under the control of the special key C and is not operated by the depression of such key, but is under the control of the totalizing mechanism, which causes the swinging of the bail F after the special key C has been depressed or set to its lowermost position. It therefore results 120 that separate and independent items may be printed on both sections of the machine and separate accumulations kept thereof, but that the accumulation or total of only one of these lists of items is printed and recorded, it being 130

understood that those items which are not footed or totalized represent such items as are not required or desired to be accumulated.

5 In order to accomplish the results just stated, I provide means arranged to be operated in the act of taking a total for rocking the shaft E farther than it is rocked by the special key C, with the result that the bail F, which has heretofore remained idle and in its normal or elevated position, will be swung downwardly, with the result hereinbefore mentioned, while the other bail, which controls the coupler, is uninterfered with and not moved farther. According to the present construction the means which I have provided to accomplish these results consists of a link or lever G, shown by itself in Fig. 8 and pivoted at its forward end to the connecting-link 226 of the totalizing mechanism. Under normal conditions when the totalizing mechanism is operated the link G is inoperative and reciprocated freely in unison with the link 226; but such link G is under the control of the special key C, which is arranged to render such link operative upon the full depression of such special key. To this end a pin-and-slot connection is provided between the special-key stem and the link G, in the present instance the link being provided with a slot G and the key-stem with a pin c⁵, whereby when the special key is in normal or elevated position the totalizing mechanism is permitted to operate in the usual and well-known manner. However, when the special key C is depressed to its full extent—that is, to the extent of the second tooth or shoulder c³—the rearward end g' of the link G, which is downwardly curved, is projected into the path of the long stud e², with the result that when the totalizing mechanism is operated and the link 226 thereby shifted rearwardly the link G is correspondingly reciprocated, whereupon the stud e², and consequently its rock-shaft E, is rocked to a greater extent than by the special key C. This extra movement has no effect upon the bail B, which has been moved to its operative position upon the first depression of the special key; but such extra movement causes the operation of the printing-controlling bail F, so that simultaneously with the depression of the total-key the bail F is placed in position to eliminate the printing action of the left-hand section of the machine. The idle condition of the bail F during the operation of the special key and its active condition upon the depression of the total-key after the special key has been set are brought about by the provision of the slots in the link D, the stud f² normally occupying a position intermediate the length of its slot, so that the movement of the link D, due to the depression of the special key, can have no effect

upon such stud and its bail F, whereas in the case of the stud b² the end of the slot which receives such latter stud simply moves away therefrom when the link D is operated by the totalizing mechanism. The relative positions of the different parts concerned with my improvements when the totalizing mechanism is operated with the special key depressed is illustrated in Fig. 7, wherein the rock-shaft E is shown as rocked rearwardly to its full extent by the link G, thereby shifting the connection or link D rearwardly to its full extent to thereby throw down the bail F to its operative position to intercept and arrest all of those hammers which are of regular construction—that is, unprovided with any cut-away portion, such as illustrated in Fig. 4.

It will be understood that the right-hand section of the present machine may be the one provided with special hammers, such as shown in Fig. 4, and that the left-hand section of the machine may be provided with the regular hammers, such as shown in Fig. 5. Furthermore, it will be understood that in case the machine is split at a plurality of points or lines any one or more of the sections may be provided with such special hammers to prevent printing action in the operation of taking a total, such result being accomplished by the proper disposition of the special hammers among the series of hammers. It is owing to this possibility and desirability of adjustment in the machine that the interference with the hammer action is made in the form of a bail, so as to intercept any series of special hammers wherever they may be arranged transversely of the printing mechanism, although such interference need not extend all the way across the printing mechanism in case the hammers of one side only of the printing mechanism are always to be the ones to be interfered with. Finally it will be understood that the relative number of special and regular hammers will vary according to the capacity of the different sections of the machine—that is, the same will vary according to the change in the location of the line of splitting in the manner hereinbefore explained.

In the present instance the machine is normally a complete machine with the full capacity of the keyboard available to the operator, but is adapted to be split by manipulation of the special key and arranged to be restored instantly to complete condition by simply releasing the special key. Thus the range of practical use or application of the adding-machine is considerably increased, inasmuch as it is not only adapted to the usual operations of printing, listing, and totaling, but is also capable of printing independent items in separate lists, one or more of which are to be footed or totalized and the

others not, as in the practice of billing or making out statements for different classes of goods with certain indicating-marks which are not to be accumulated, followed by 5 amounts or values which are to be accumulated.

I claim—

1. In an adding-machine, the combination, with the printing, accumulating and totalizing mechanisms, of means for rendering the machine either complete or split into sections, and means for eliminating the printing of a total from a section at the will of the operator.
- 15 2. In an adding-machine, the combination, with the printing, accumulating and totalizing mechanisms, of means for rendering the machine either complete or split into sections, and means controlled by the totalizing mechanism for eliminating the printing of a total from a section at the will of the operator.
- 25 3. In an adding-machine, the combination, with the printing, accumulating and totalizing mechanisms, of means for rendering the machine either complete or split into sections, and means normally inoperative to permit the printing of separate totals when the machine is split but arranged to be operated by the totalizing mechanism for eliminating the 30 printing of a total from a section at the will of the operator.
- 35 4. In an adding-machine, the combination, with the printing, accumulating and totalizing mechanisms, of means for rendering the machine either complete or split into sections, mechanism normally inoperative to permit the printing of separate totals when the machine is split, and means for operatively connecting said mechanism with the totalizing 40 mechanism to cause the eliminating of the printing of a total from a section at the will of the operator.
- 45 5. In an adding-machine, the combination, with the printing, accumulating and totalizing mechanisms, of means for rendering the machine either complete or split into sections, and key-controlled means actuated by the totalizing mechanism for eliminating the printing of a total from a section at the will 50 of the operator.
- 55 6. In an adding-machine, the combination, with the printing, accumulating and totalizing mechanisms, of means for rendering the machine either complete or split into sections, mechanism arranged to eliminate the printing of a total from a section, and a key operatively connected with said means and adapted to also cause operative connection between 60 said eliminating mechanism and the totalizing mechanism.
- 65 7. In an adding-machine, the combination, with the printing, accumulating and totalizing mechanisms, of means for rendering the machine either complete or split into sections,

mechanism arranged to eliminate the printing of a total from a section, an operating connection therefor, and a key controlling said connection and adapted to operatively connect the same with the totalizing mechanism.

8. In an adding-machine, the combination, with the printing, accumulating and totalizing mechanisms, of means for rendering the machine either complete or split into sections, mechanism arranged to eliminate the printing of a total from a section, an operating connection therefor, and a key controlling said means and also said connection and adapted to operatively connect the same with the totalizing mechanism.

9. In an adding-machine, the combination, with the printing, accumulating and totalizing mechanisms, of means for rendering the machine either complete or split into sections, mechanism arranged to eliminate the printing of a total from a section and a single key controlling the action of said means and of said eliminating mechanism.

10. In an adding-machine, the combination, with the printing, accumulating and totalizing mechanisms, of means for rendering the machine either complete or split into sections, mechanism arranged to eliminate the printing of a total from a section, and a single key operatively connected with said means and arranged to cause operative connection between the eliminating mechanism and the totalizing mechanism, said key having two operative positions, in one of which said means are actuated and in the other of which said connection is made with the totalizing mechanism.

11. In an adding-machine, the combination, with the accumulating and totalizing mechanisms and with the printing mechanism and its series of hammers for causing impressions, of a means for rendering the machine either complete or split into sections, and means for preventing the action of the hammers of one of the sections at the will of the operator.

12. In an adding-machine, the combination, with the accumulating and totalizing mechanisms and with the printing mechanism and its series of hammers for causing impressions, of means for rendering the machine either complete or split into sections, and means operated by the totalizing mechanism for preventing the action of the hammers of one of the sections at the will of the operator.

13. In an adding-machine, the combination, with the accumulating and totalizing mechanisms and with the printing mechanism and its series of hammers for causing impressions, of means for rendering the machine either complete or split into sections, and means normally inoperative to permit

the hammers of the sections to act when the machine is split but arranged to be actuated by the totalizing mechanism for interfering with the action of the hammers of one of the sections at the will of the operator.

14. In an adding-machine, the combination, with the accumulating and totalizing mechanisms and with the printing mechanism and the series of hammers for causing impressions, of means for rendering the machine either complete or split into sections, means normally inoperative to permit the hammers of the sections to act when the machine is split, and an operating connection under the control of the operator and adapted to be connected with said last-named means and the totalizing mechanism to prevent the hammers of one section from acting.

15. In an adding-machine, the combination, with the accumulating and totalizing mechanisms and with the printing mechanism and the series of hammers for causing impressions, of means for rendering the machine either complete or split into sections, means normally inoperative to permit the hammers of the sections to act when the machine is split; an operating connection therefor, and a key for controlling both said splitting means and said connection, whereby the machine may be split and said connection may be operatively connected with the totalizing mechanism to prevent the operation of the hammers of one section in the act of taking a total.

35 16. In an adding-machine, the combination, with the printing, accumulating and totalizing mechanisms, of means for rendering the machine either complete or split into sections, and means for eliminating the printing of a total from a section at the will of the operator comprising a bail adapted to interfere with the hammers of the particular section, and an operating connection under the control of the operator between such bail and the totalizing mechanism.

17. In an adding-machine, the combination, with the printing, accumulating and totalizing mechanisms, of means for rendering the machine either complete or split into sections, and means for eliminating the printing of a total from a section at the will of the operator comprising a bail arranged to be placed in the path of all the hammers, the hammers of the section not interfered with being cut away to avoid arrest by the bail when in operative position, and an operating connection under the control of the operator between such bail and the totalizing mechanism.

60 18. In an adding-machine, the combination, with the printing, accumulating and totalizing mechanisms, of means for rendering the machine either complete or split into sections, and means for eliminating the printing of a total from a section at the will of the operator comprising a bail normally pressed to an inoperative position but arranged to be placed in the path of the hammers of said particular section, and an operating connection under the control of the operator between such bail and the totalizing mechanism.

65 19. In an adding-machine, the combination, with the printing, accumulating and totalizing mechanisms, of means for splitting the machine into sections, a bail adapted to be interposed in the path of the hammers of one of the sections to prevent their action, and a key-controlled operating connection between said bail and the totalizing mechanism to operate the former whenever such key is operated in the totalizing operation.

70 20. In an adding-machine, the combination, with the printing, accumulating and totalizing mechanisms, of means for splitting the machine into sections, a bail adapted to be interposed in the path of the hammers of one of the sections to prevent their action, an operating connection for said splitting means and for said bail, and a key for actuating said connection to split the machine and also for operatively connecting the same with the totalizing mechanism to operate the bail to arrest the hammers of one of the sections.

75 21. In an adding-machine, the combination, with the printing, accumulating and totalizing mechanisms, of means for splitting the machine into sections, a bail adapted to be interposed in the path of the hammers of one of the sections to prevent their action, an operating device for said splitting means and for said bail, an arm actuated by the totalizing mechanism but normally inactive, and a key for actuating said connection to split the machine and also for moving said arm to an active position between said totalizing mechanism and said operating device, whereby the bail is operated to arrest the hammers of one of the sections.

80 22. In an adding-machine, the combination, with the printing, accumulating and totalizing mechanisms, of means for splitting the machine into sections, a bail adapted to be interposed in the path of the hammers of one of the sections to prevent their action, an operating device for said splitting means and for said bail, a swinging arm actuated by the totalizing mechanism but normally inactive, and a key having a stem with a pin-and-slot connection with said arm for swinging the same into the path of said operating device whereby the latter is actuated automatically by the totalizing mechanism and the bail operated to arrest the hammers of one of the sections.

85 23. In an adding-machine, the combination, with the printing, accumulating and totalizing mechanisms, of means for splitting the machine into sections, a bail adapted to be interposed in the path of the hammers of

one of the sections to prevent their action, said bail being normally spring-pressed to a position of non-interference with said hammers, and a key-controlled operating connection

5 between the totalizing mechanism and the bail to operate the latter against its spring tension whenever such key is operated in the totalizing operation.

24. In an adding-machine, the combination, with the printing, accumulating and totalizing mechanisms, of means for splitting the machine into sections, means for eliminating the printing action of one of the sections, an operating device for both of said means, a 10 key operatively connected with said device for partially moving the same to actuate the splitting means, and an arm under the control of the key and arranged to be actuated by the totalizing mechanism to further move said device for operating said eliminating means.

25. In an adding-machine, the combination, with the printing, accumulating and totalizing mechanisms, of means for splitting the machine into sections, means for eliminating the printing action of one of the sections, an operating device for both of said means, comprising a rock-shaft and a link having a pin-and-slot connection with both of said means, a key for operating said rock-shaft to actuate said splitting means without actuating the said eliminating means, and an operating connection controlled by the key and arranged to be operated by the totalizing mechanism to further rock said shaft to actuate the eliminating means.

30 26. In an adding-machine, the combination, with the printing, accumulating and totalizing mechanisms, of means for splitting the machine into sections, means for eliminating the printing action of one of the sections, an operating device for both of said means comprising a rock-shaft operatively connected with both of said means, an arm on said shaft, a key having a stem arranged 40 to be projected against said arm to rock said shaft to a partial extent to actuate the splitting means, and an operating connection actuated by the totalizing mechanism for rocking said shaft to a further extent to actuate 45 said eliminating means.

27. In an adding-machine, the combination, with the printing, accumulating and totalizing mechanisms, of means for splitting the machine into sections, means for eliminating the printing action of one of the sections, an operating device for both of said means comprising a rock-shaft operatively connected with both of said means, an arm on said shaft, a key having a stem arranged 50 to be projected against said arm to rock said shaft to a partial extent to actuate the splitting means, and an operating connection mounted on the totalizing mechanism and having a pin-and-slot connection with the key,

55 said operating connection being arranged to be moved by the key to a position to actuate said rock-shaft to operate the eliminating means.

28. In an adding-machine, the combination, with the printing, accumulating and totalizing mechanisms, of means for splitting the machine into sections, means for eliminating the printing action of one of the sections, an operating device for both of said means, comprising a rock-shaft operatively 70 connected with both of said means, an arm on said shaft, a key having a stem arranged to be projected against said arm to rock said shaft to a partial extent to actuate the splitting means, said key having two set positions, the first of which operates the splitting means, and a connection actuated by the totalizing mechanism and moved by the key when operated for its second set position to bring said connection in operative relationship with the rock-shaft to actuate the latter to its full extent and thereby operate said eliminating means.

29. In an adding-machine, the combination, with the printing, accumulating and totalizing mechanisms, of means for splitting the machine into sections, means for eliminating the printing action of one of the sections, an operating device for both of said means comprising a rock-shaft operatively 90 connected with both of said means, an arm on said shaft, a key having a stem arranged to be projected against said arm to rock said shaft to a partial extent to actuate the splitting means, and a swinging arm mounted on 100 the totalizing mechanism and having a pin-and-slot connection with the key whose full depression shifts said arm to a position to actuate the rock-shaft when the totalizing mechanism is operated to thereby operate 105 the eliminating means.

30. In an adding-machine, the combination, with the printing, accumulating and totalizing mechanisms, of means for splitting the machine into sections, means for eliminating the printing action of one of the sections, an operating device for both of said means comprising a rock-shaft operatively connected with both of said means, an arm on said shaft, a key having a stem arranged 110 to be projected against said arm to rock said shaft to a partial extent to actuate the splitting means, said totalizing mechanism having a link 226 reciprocated in the act of taking a total, and a swinging arm pivoted on 120 said link and arranged to be moved by said key to a position to rock said shaft when the totalizing mechanism is operated to thereby operate said eliminating means.

31. In an adding-machine, the combination, with the printing mechanism thereof having a series of printing devices corresponding to different denominations, of means ar-

ranged to be adjusted in position to coöperate with any one of said printing devices to split the machine between any two denominations.

32. In an adding-machine, the combination, with the printing mechanism thereof having a series of printing devices corresponding to different denominations, of a device arranged to coöperate with any one of said printing devices to split the machine between any two denominations, and a support on which said device may be held in different positions relating to said series of printing devices to split the machine at a line according to its position on said support.

33. In an adding-machine, the combination, with the printing mechanism thereof having a series of printing devices corresponding to different denominations, of a device arranged to coöperate with any one of said printing devices to split the machine between any two denominations, and a cross-shaft having a series of grooves corresponding with the spaces between said printing devices and adapted to support said splitting device in any one of the grooves in which it is placed.

34. In an adding-machine, the combination, with the printing mechanism thereof having a series of printing devices corresponding to different denominations, of means arranged to be adjusted in position to coöperate with any one of said printing devices to split the machine between any two denominations comprising an arm arranged to be shifted to different positions, and a support extending transversely of the printing mechanism and having a series of grooves any one of which is arranged to receive said arm and whereby such arm may be adjusted to different positions thereon.

35. In an adding-machine, the combination, with the printing mechanism including its hammers and controlling-latches, of special latches arranged adjacent each other at the line of split, and a movable arm adapted, when in one position, to coöperate with both special latches to make the machine complete and, when in another position, to render the machine split.

36. In an adding-machine, the combination, with the printing mechanism including its hammers and controlling-latches, of special latches arranged adjacent each other at the line of split, and a movable arm adapted to swing between such special latches and having projections arranged to engage both of said special latches to transfer the hammer-action for cipher-printing.

37. In an adding-machine, the combination, with the printing mechanism including its hammers and controlling-latches, of special latches arranged adjacent each other at the line of split and having reversely-arranged recesses, and a movable arm adapted to

swing between such special latches and having projections positioned in such recesses when in operative position to couple said special latches together for transferring the hammer-action for cipher-printing.

38. In an adding-machine, the combination, with the printing mechanism including its hammers and controlling-latches, of special latches arranged adjacent each other at the line of split, a shaft on which the special latches and the regular latches are supported in removable manner whereby the relative arrangement of the special and the regular latches may be changed to vary the line of split, and a movable arm arranged to coöperate with both of said special latches and adapted, when in operative position, to transfer hammer-action across the line of split for cipher-printing.

39. In an adding-machine, the combination, with the printing mechanism including its hammers and controlling-latches, of special latches arranged adjacent each other at the line of split, a shaft on which the special latches and the regular latches are supported in removable manner whereby the relative arrangement of the special and the regular latches may be changed to vary the line of split, a movable arm arranged to coöperate with both of said special latches and adapted, when in operative position, to transfer the hammer-action across the line of split for cipher-printing, and a support for said arm having means whereby such arm may be adjusted in position to correspond with the adjustment of the special latches.

40. In an adding-machine, the combination, with the printing mechanism including its hammers and controlling-latches, of special latches arranged adjacent each other at the line of split, a shaft on which the special latches and the regular latches are supported in removable manner whereby the relative arrangement of the special and the regular latches may be changed to vary the line of split, a movable arm arranged to coöperate with both of said special latches and adapted, when in operative position, to transfer the hammer-action across the line of split for cipher-printing, and a shaft having a series of grooves adapted to receive said arm and support it at any position according to which ever groove said arm is inserted into.

41. In an adding-machine, the combination, with the printing mechanism including its hammers and controlling-latches, of special latches arranged adjacent each other at the line of split, a shaft on which the special latches and the regular latches are supported in removable manner whereby the relative arrangement of the special and the regular latches may be changed to vary the line of split, a movable arm arranged to coöperate with both of said special latches to transfer

the hammer-action across the line of split for cipher-printing, and a rod forming a support or axis for said arm which is provided with an open-ended slot at one end to fit over said 5 supporting-rod.

42. In an adding-machine, the combination, with the printing mechanism including its hammers and controlling-latches, of special latches arranged adjacent each other at 10 the line of split, a shaft on which the special latches and the regular latches are supported in removable manner whereby the relative arrangement of the special and the regular latches may be changed to vary the line of 15 split, a rod or support, a movable arm arranged to coöperate at its rearward end with both of said special latches to form a coupler to transfer the hammer-action across the line of split for cipher-printing, said arm being pivoted intermediate its length on said rod and an operating means coöperating with the 20 forward end of the arm to operate the same.

43. In an adding-machine, the combination, with the printing mechanism including 25 its hammers and controlling-latches, of special latches arranged adjacent each other at the line of split, a shaft on which the special latches and the regular latches are supported in removable manner whereby the relative 30 arrangement of the special and the regular latches may be changed to vary the line of split, a rod or support, a movable arm arranged to coöperate at its rearward end with both of said special latches to form a coupler 35 to transfer the hammer-action across the line of split for cipher-printing, said arm being pivoted intermediate its length on said rod and a key-controlled bail arranged to rock against the forward end of the arm to rock 40 the latter to an inoperative position.

44. In an adding-machine, the combination, with the printing mechanism including 45 its hammers and controlling-latches, of special latches arranged adjacent each other at the line of split, a shaft on which the special latches and the regular latches are supported in removable manner whereby the relative arrangement of the special and the regular latches may be changed to vary the line of 50 split, a rod or support, a movable arm arranged to coöperate at its rearward end with both of said special latches to form a coupler to transfer the hammer-action across the line of split for cipher-printing, said arm being pivoted intermediate its length on said rod and normally held with a yielding pressure to 55 an operative position to make the machine complete, and means, coöperating with the forward end of the arm, to operate the same.

45. In an adding-machine, the combination, with the printing mechanism including its hammers and controlling-latches, of special latches arranged adjacent each other at the line of split, a shaft on which the special

latches and the regular latches are supported 65 in removable manner whereby the relative arrangement of the special and the regular latches may be changed to vary the line of split, a rod or support, a movable arm arranged to coöperate at its rearward end with 70 both of said special latches to form a coupler to transfer the hammer-action across the line of split for cipher-printing, said arm being pivoted intermediate its length on said rod, a bail B arranged to rock against and thereby 75 operate said arm, a rock-shaft b connected with such bail, and a key operatively connected with the rock-shaft.

46. In an adding-machine, the combination, with the printing mechanism including 80 its hammers and controlling-latches, of special latches arranged adjacent each other at the line of split, a shaft on which the special latches and the regular latches are supported in removable manner whereby the relative 85 arrangement of the special and the regular latches may be changed to vary the line of split, a rod or support, a movable arm arranged to coöperate at its rearward end with both of said special latches to form a coupler 90 to transfer the hammer-action across the line of split for cipher-printing, said arm being pivoted intermediate its length on said rod, a bail B arranged to rock against and thereby 95 operate said arm, a rock-shaft b connected with said bail, and a key-controlled second rock-shaft E, and a connecting-link D between said rock-shafts.

47. In an adding-machine, the combination, with the printing mechanism including 100 its hammers and controlling-latches, of special latches arranged adjacent each other at the line of split, a shaft on which the special latches and the regular latches are supported in removable manner whereby the relative 105 arrangement of the special and the regular latches may be changed to vary the line of split, a rod or support, a movable arm arranged to coöperate at its rearward end with both of said special latches to form a coupler 110 to transfer the hammer-action across the line of split for cipher-printing, said arm being pivoted intermediate its length on said rod, a bail B arranged to rock against and thereby 115 operate said arm, a rock-shaft b connected therewith, a spring b³ for holding said bail in an inoperative position, and a key-controlled operating connection for actuating said rock-shaft and bail.

48. In an adding-machine, the combination, with the printing mechanism including 120 its hammers and controlling-latches, of special latches arranged adjacent each other at the line of split, a shaft on which the special latches and the regular latches are supported 125 in removable manner whereby the relative arrangement of the special and the regular latches may be changed to vary the line of

split, a rod or support, a movable arm arranged to coöperate at its rearward end with both of said special latches to form a coupler to transfer the hammer-action across the line of split for cipher-printing, said arm being pivoted intermediate its length on said rod, a bail B arranged to rock against and thereby operate said arm, a rock-shaft b connected with said bail, a second rock-shaft E which is key-controlled, and a connecting-link D having pin-and-slot connections with said shafts.

49. In an adding-machine, the combination, with the accumulating and totalizing mechanisms, and with the printing mechanism including its hammers, of mechanism for splitting the machine into sections, means for operating said last-named mechanism comprising a bail, a second bail arranged to arrest the hammers of a section to prevent printing action as to such section, and means for operating said bails consisting of crank-arms on such bails, a link D operatively con-

nected with such crank-arms and arranged to rock the splitting-bail in advance of the other bail, and means for reciprocating said link at the will of the operator.

50. In an adding-machine, the combination, with the accumulating and totalizing mechanisms, and with the printing mechanism including its hammers, of mechanism for splitting the machine into sections, means for operating said last-named mechanism comprising a bail, a second bail arranged to arrest the hammers of a section to prevent printing action as to such section, and means for operating said bails consisting of crank-arms on such bails, a link D having pin-and-slot connections with the crank-arms but arranged to rock the splitting-bail in advance of the other bail, and means for reciprocating said link at the will of the operator.
